DISPENSING CONTAINER FOR PILLS OR TABLETS

Frank A. Goodrich, Kalamazoo, Mich.

Application July 15, 1954, Serial No. 31,460

Term of patent 14 years

(Cl. D52—2)

fig. 1

fig. 2

fig. 3

Figure 1 is a perspective view of a dispensing container for pills or tablets embodying my new design;

The pills shown in broken outline are for illustrative purposes only.

I claim:

The ornamental design for a dispensing container for pills or tablets, as shown and described.
